DATA PROCESSING SYSTEM CONSOLE

Walter Furlani, Endicott, and Edward J. Sabella, Vestal,
N.Y., assignors to International Business Machines
Corporation, New York, N.Y., a corporation of New
York

Filed Aug. 29, 1962, Ser. No. 71,492

Term of patent 14 years

(Cl. D64—11)

FIG. 1

FIG. 2

Des. 198,879

PAGE 2

FIG. 3

FIG. 4

FIG. 5

FIG. 6

FIG. 1 is a front perspective view of a data processing system console embodying our new design.

FIG. 2 is a side elevational view.

FIG. 3 is another side elevational view showing the side opposite that shown in FIG. 2.

FIG. 4 is a rear elevational view.

FIG. 5 is a front elevational view.

FIG. 6 is a top plan view of the data processing system console shown in the preceding five figures.

The essentials of our design reside in the portions shown in solid lines in the drawing.

We claim:

The ornamental design for a data processing system console, as shown and described.
